UNITED STATES PATENT OFFICE.

EDWARD A. ROZIER, SR., OF SPARTA, GEORGIA, ASSIGNOR TO ELLA LOU ROZIER, OF SPARTA, GEORGIA.

GIN ATTACHMENT.

1,018,273.

Specification of Letters Patent.

Patented Feb. 20, 1912.

Application filed June 23, 1911. Serial No. 634,903.

To all whom it may concern:

Be it known that I, EDWARD A. ROZIER, Sr., a citizen of the United States, and a resident of Sparta, in the county of Hancock, State of Georgia, have invented a new and useful Improvement in Gin Attachments, of which the following is a specification.

My invention is an improvement in gin attachments, and has for its object the provision of a simple device of the character specified for absolutely removing all of the motes and black specks in cotton during the operation of ginning, and for also removing earth stains, and which may be applied to the ordinary or usual gin without any material changes in the said gin.

In the drawings: Figure 1 is a vertical longitudinal section of the improvement; Fig. 2 is an enlarged perspective view of a portion of the brush; Fig. 3 is a similar view of the stationary brush; Fig. 4 is an enlarged vertical section of the improvement on the line of the brush.

In the present embodiment of the invention the case 1 of the gin is provided with the usual feed opening 2. Bars 3 are arranged transversely of the feed opening, and gin saw comprising a disk 4 provided with teeth 5 projects a portion of its periphery between each pair of adjacent bars.

The disks are secured to a common shaft 6 journaled in the frame, and spacing collars 7 are arranged between the adjacent disks. Each of the bars 3 is provided with a depressed or rearwardly curved portion 8 intermediate its ends, and a cylindrical brush 9 is secured on a shaft 10 journaled behind the shaft 6 and parallel therewith.

The improvement comprises a casing, box, or receptacle 11 arranged on the bottom of the case 1 between the shafts 6 and 10, and a plurality of tubes 12 extends upwardly from the box or casing between the said shafts and slightly above the level of the same. Each of the tubes is substantially rectangular in cross section, open at its top, and communicating with the box or casing at its bottom.

A pair of shafts 13 and 14 is journaled transversely of the case 1 near the top thereof, and another pair of shafts 15 and 16 is journaled transversely of the receptacle 11. All of the shafts 13 to 16, inclusive, are

parallel and in vertical alinement, and each shaft is provided with a plurality of toothed wheels 17.

The wheels 17 on each shaft are arranged alternately with respect to the wheels on the other member of the pair, and the wheels on the shafts 13 and 16 register or are in alinement, as are also the wheels on shafts 14 and 15. Each registering pair of wheels 17 is also in alinement with a tube 11.

The shafts 13 and 14 are journaled in bearings 18 on the inner face of the top of the case 1, and sprocket wheels 19 and 20 are secured to the respective ends thereof. A sprocket chain 21 connects wheel 20 with a sprocket wheel 22 on the adjacent end of shaft 16, and a chain 23 connects wheel 19 with a sprocket wheel 24 on the adjacent end of shaft 15.

A sprocket wheel 25 is secured to one end of shaft 14, and a chain 26 connects the said wheel with a similar wheel 27 on the adjacent end of shaft 15. Shaft 15 is provided with a worm wheel 28 outside of the wheel 24, and a worm 29 on a shaft 30 meshes with the said worm wheel to drive the shafts. The worm shaft 30 is driven in any suitable manner, as are also the shafts 6 and 10.

An endless belt is supported on each pair of registering wheels 17. Each of the said belts is composed of spaced flexible steel bands 31 and 32 connected at spaced intervals by eyelets 33. Bristles 34 are arranged transversely between the plates and extend beyond each side thereof, as shown in Fig. 2. A band 35 of tape, of cotton, or like fabric material is arranged between one of the bands 31 or 32, the latter in the present instance, and the bristles. Each of the said endless bands is constructed as follows. The bristles are laid in glue on the band 35, the glue being applied to the band, and the bristles laid crosswise thereon. The steel bands are then laid, and the eyelets are placed, securing the parts together and also serving as openings for engagement by the teeth of the wheels 17. The wheels thus move the belts positively.

At the top of each of the tubes 12 the device shown more particularly in Fig. 3 is arranged. The said device comprises a holder consisting of a tube or shell 37 secured transversely of the tube between the side walls thereof and near the front runs

of the belts. It will be noticed that the front side of each tube is higher than the rear side, the rear side being cut away on a bevel, as indicated at 38.

5 A strip 39 of suitable material is doubled upon itself and upon a transversely arranged tuft 40 of bristles, and the ends of the strip are inserted in the holder and held in any suitable manner. It will be noticed that the 10 runs of the belts pass on opposite sides of the holder 37, the front run of each belt passing close to the holder.

15 A portion of each disk 4 projects between two adjacent tubes, and an inspection of Fig. 4 will show that both sides of the disks are engaged by the edge of a belt, that is, by the extended ends of the bristles. In addition, each disk is engaged on both sides by the ends of the bristles 40. The engagement of the bristles 40 is at the edge of the 20 saw, so that the teeth are brushed by the said bristles. Both runs of the belts engage the teeth, and each saw is engaged in two places by the front runs and in two places 25 by the rear runs, and in one place by the bristles 40.

In operation, the cotton is fed in the usual manner and the seeds are removed as the cotton is drawn through between the bars, 30 the seeds falling from the ends of the bars through the opening 41 between the said front ends and the front of the case 1. The belts travel very slowly, probably two feet per minute, and as they move they carry 35 away the motes, specks and dirt that are combed from the lint by the bristles before the said lint is removed from the saws by the brush 9. The said impurities are drawn down the tubes and removed by the exhaust- 40 apparatus. The cotton is rubbed, combed or brushed between the moving brushes, that is, the belts, and the stationary brushes, that is, the bristles 40. The brushes are especially effective, since they operate on the smallest 45 possible quantities of cotton possible, namely, the little tufts drawn through the bars by the teeth of the disks.

I claim:

1. In a cotton gin, the combination with 50 the saws, and the rotating brush, of a receptacle having an outlet arranged below and between the saws and the said brush, said receptacle having a tube extending upwardly between each adjacent pair of saws above the axis of the saws, a pair of vertically aligned parallel shafts above the tubes, a pair of vertically aligned parallel shafts in the receptacle below the tubes, a series of toothed wheels on each shaft, the wheels of 55 each member of each pair being arranged alternately with respect to the wheels on the other member of the pair, and in register with the wheels of the corresponding shaft of the other pair, an endless belt supported 60 on each registering pair of wheels, each belt 65

comprising spaced superposed flexible metallic belts, a belt of fabric material between the said belts, bristles arranged transversely of one face of the last named belt and extending beyond the edges of the belts on 70 both sides, eyelets connecting the belts at spaced intervals and engaging the teeth of the wheels, the ends of the bristles bearing against the edge of a saw at each side, means for moving the belts, and a stationary brush 75 secured to the top of each tube, each brush comprising a holder arranged transversely of the tube, a strip doubled upon itself and having its ends received in the holder, and bristles between the doubled portion of the 80 strips, and means for drawing a current of air through the tubes and into the receptacle.

2. In a cotton gin, the combination with 85 the saws, and the rotating brush, of a receptacle having an outlet arranged below and between the saws and the said brush, said receptacle having a tube extending upwardly between each adjacent pair of saws above the axis of the saws, a pair of vertically aligned parallel shafts above the tubes, a pair of vertically aligned parallel shafts in the receptacle below the tubes, a series of toothed wheels on each shaft, the wheels of each member of each pair being arranged 90 alternately with respect to the wheels on the other member of the pair, and in register with the wheels of the corresponding shaft of the other pair, an endless belt supported 95 on each registering pair of wheels, each belt comprising spaced superposed flexible metallic belts, a belt of fabric material between the said belts, bristles arranged transversely of one face of the last named belt and extending beyond the edges of the belts on 100 both sides, eyelets connecting the belts at spaced intervals and engaging the teeth of the wheels, the ends of the bristles bearing against the edge of a saw at each side, means for moving the belts, and a stationary brush 105 secured to the top of each tube, and means for drawing a current of air through the tubes into the receptacle.

3. In a cotton gin, the combination with 115 the saws, and the rotating brush, of a receptacle having an outlet arranged below and between the saws and the said brush, said receptacle having a tube extending upwardly between each adjacent pair of saws above the axis of the saws, a pair of vertically aligned parallel shafts above the tubes, a pair of vertically aligned parallel shafts in the receptacle below the tubes, a series of toothed wheels on each shaft, the wheels of each member of each pair being arranged alternately with respect to the wheels of the other member of the pair, and in register with the wheels of the corresponding shaft of the other pair, an endless belt supported on each 120 registering pair of wheels, each belt comprising 125

ing spaced superposed flexible metallic belts, a belt of fabric material between the said belts, bristles arranged transversely of one face of the last named belt and extending beyond the edges of the belts on both sides, eyelets connecting the belts at spaced intervals and engaging the teeth of the wheels, the ends of the bristles bearing against the edge of a saw at each side, means for moving the belts, and a stationary brush secured to the top of each tube.

4. In a cotton gin, the combination with the saws, and the rotating brush, of a receptacle having an outlet arranged below and between the saws and the said brush, said receptacle having a tube extending upwardly between each adjacent pair of saws above the axis of the saws, a pair of vertically alined parallel shafts above the tubes, 15 a pair of vertically alined parallel shafts in the receptacle below the tubes, a series of toothed wheels on each shaft, the wheels of each member of each pair being arranged alternately with respect to the wheels of the 20 other member of the pair, and in register with the wheels of the corresponding shaft of the other pair, an endless belt supported on each registering pair of wheels, each belt having openings for engagement by the 25 teeth of the wheels and having bristles extending laterally from each side edge and engaging the edge of a saw, means for moving the belts, and a stationary brush at the top of each tube, said brushes having laterally 30 extending bristles engaging the teeth of the saws at each side of each tube, and means for drawing a current of air through the tubes into the receptacle.

5. In a cotton gin, the combination with the saws, and the rotating brush, of a receptacle having an outlet arranged below and between the saws and the said brush, said receptacle having a tube extending upwardly between each adjacent pair of saws 40 above the axis of the saws, a pair of vertically alined parallel shafts above the tubes, a pair of vertically alined parallel shafts in the receptacle below the tubes, a series of toothed wheels on each shaft, the wheels of 45 each member of each pair being arranged alternately with respect to the wheels of the other member of the pair, and in register with the wheels of the corresponding shaft of the other pair, an endless belt supported 50 on each registering pair of wheels, each belt having openings for engagement by the teeth of the wheels and having bristles extending laterally from each side edge and engaging the edge of a saw, means for moving the belts, and a stationary brush at the top of each tube, said brushes having laterally 55 extending bristles engaging the teeth of the saws at each side of each tube.

6. In a cotton gin, the combination with the saws, and the rotating brush, of a re-

ceptacle having an outlet arranged below and between the saws and the said brush, said receptacle having a tube extending upwardly between each adjacent pair of saws above the axis of the saws, a plurality of 70 endless belts supported in the tubes for movement longitudinally thereof, each belt having laterally extending bristles at each side edge, each saw being engaged at opposite sides by the bristles, means for moving the belts, a stationary brush at the top of each tube and between the runs of the belt in the tube, each of the said brushes having bristles extending laterally from both sides and engaging the teeth of the saws, and 75 means for drawing a current of air through the tubes into the receptacle.

7. In a cotton gin, the combination with the saws, and the rotating brush, of a receptacle having an outlet arranged below and between the saws and the said brush, said receptacle having a tube extending upwardly between each adjacent pair of saws above the axis of the saws, a plurality of 80 endless belts supported in the tubes for movement longitudinally thereof, each belt having laterally extending bristles at each side edge, each saw being engaged at opposite sides by the bristles, means for moving the belts, a stationary brush at the top of each tube and between the runs of the belt in the tube, each of the said brushes having bristles extending laterally from both sides and engaging the teeth of the saws, and 85

8. In a cotton gin, the combination with the saws, and the rotating brush, of a receptacle having an outlet arranged below and between the saws and the said brush, said receptacle having a tube extending upwardly between each adjacent pair of saws above the axis of the saws, a plurality of 90 endless belts supported in the tubes for movement longitudinally thereof, each belt having laterally extending bristles at each side edge, each saw being engaged at opposite sides by the bristles, means for moving the belts, a stationary brush at the top of each tube and between the runs of the belt in the tube, each of the said brushes having bristles extending laterally from both sides and engaging the teeth of the saws, and 95

9. In a gin, the combination with the saws and the cleaning brush for the saws, of a cleaning device arranged between the brush and the saws, said device comprising a plurality of endless belts arranged alongside each other, each saw having its edge extending between adjacent belts, and each belt having laterally extending bristles at each side edge engaging the adjacent faces of the adjacent saws, means for moving the belts, a receptacle below the belts and into which 115 they extend, said receptacle having a tube inclosing a portion of each belt and extending above the axis of the saws, a stationary brush at the top of each tube, each brush having laterally and oppositely extending 120

125

130

bristles engaging the teeth of the adjacent saws, and means for exhausting the air from the receptacle.

10. In a gin, the combination with the saws and the cleaning brush for the saws, of a cleaning device arranged between the brush and the saws, said device comprising a plurality of endless belts arranged alongside each other, each saw having its edge extending between adjacent belts, and each belt having laterally extending bristles at each side edge engaging the adjacent faces of the adjacent saws, means for moving the belts, a receptacle below the belts and into which they extend, said receptacle having a tube inclosing a portion of each belt and extending above the axis of the saws, a stationary brush at the top of each tube, each brush having laterally and oppositely extending bristles engaging the teeth of the adjacent saws.

11. In a gin, the combination with the saws and the cleaning brush for the saws, of a cleaning device arranged between the brush and the saws, said device comprising a plurality of endless belts arranged alongside each other, each saw having its edge extending between adjacent belts, and each belt having laterally extending bristles at each side edge engaging the adjacent faces of the adjacent saws, means for moving the belts, a receptacle below the belts and into which they extend, said receptacle having a tube inclosing a portion of each belt and extending above the axis of the saws, and means for exhausting the air from the receptacle.

12. In a gin, the combination with the saws and the cleaning brush for the saws, of a cleaning device arranged between the brush and the saws, said device comprising a plurality of endless belts arranged alongside each other, each saw having its edge extending between adjacent belts, and each belt having laterally extending bristles at each side edge engaging the adjacent faces of the adjacent saws, means for moving the

belts, a receptacle below the belts and into which they extend, said receptacle having a tube inclosing a portion of each belt and extending above the axis of the saws.

50

13. In a gin, the combination with the saws and the cleaning brush for the saws, of a cleaning device arranged between the brush and the saws, said device comprising a plurality of endless belts arranged alongside each other, each saw having its edge extending between adjacent belts, and each belt having laterally extending bristles at each side edge engaging the adjacent faces of the adjacent saws, means for moving the belts, an enclosure for the lower ends of the belts, and means for exhausting the air from the enclosure.

55

60

14. In a gin, the combination with the saws and the cleaning brush for the saws, of a cleaning device arranged between the brush and the saws, said device comprising a plurality of endless belts arranged alongside each other, each saw having its edge extending between adjacent belts, and each belt having laterally extending bristles at each side edge engaging the adjacent faces of the adjacent saws, and means for moving the belts.

65

70

15. In a gin, the combination with the saws, of a cleaning device for the lint comprising a belt on each side of the saws and at the rear thereof, each belt having laterally extending bristles engaging the lint on the teeth of the saws.

75

80

16. In a gin, the combination with the saws, of a cleaning device for the lint on the saws comprising a brush at each side of each saw, said brush having bristles engaging the cotton on the saws, and means for moving the brushes in the direction of movement of the saws and at a lower speed.
